HERBERT E. METCALF, OF SAN LEANDRO, CALIFORNIA, ASSIGNOR TO THE MAGNAVOX COMPANY, OF OAKLAND, CALIFORNIA, A CORPORATION OF ARIZONA

SIGNAL REPRODUCER

Application filed October 26, 1927. Serial No. 228,872.

This invention relates to reproduction of electric signals, and especially to a device whereby telephonic currents are converted into sound of large volume.

5 One form of reproducer or "loud speaker" utilizes the dynamic principle for moving an air actuator, such as a diaphragm or cone. In this form of speaker, there is provided a magnet, (either permanent or electromagnetic) which provides an intense and constant magnetic field across a narrow air gap. A movable coil is disposed in this field, and is fed with the currents that are to be translated into sound waves. The reaction between the 15 varying magnetic field produced by this coil and the magnetic field of the constant magnet causes movement of the coil, which in turn imparts movement to the air actuating device mechanically connected to the coil.

20 Since the movement of the coil follows in accordance with the variations of the currents fed thereto, it is evident that faithful reproduction is obtained.

It is of course to be understood that the device is reversible in function; that is, sound waves can be converted into electric impulses by actuating the coil in accordance with these waves.

It is one of the objects of my invention 30 to improve in general this form of reproducer.

It is another object of my invention to provide an improved mechanical arrangement of the elements making up the speaker; and especially to provide a convenient form of movable support for the movable coil, and to arrange the connections thereto in such a way that there shall be no undesirable rattling or other extraneous sounds.

My invention possesses many other advantages, and has other objects which may be made more easily apparent from a consideration of one embodiment of my invention. For this purpose I have shown a form in the drawings accompanying and forming part of 45 the present specification. I shall now proceed to describe this form in detail, which illustrates the general principles of my invention; but it is to be understood that this detailed description is not to be taken in a 50 limiting sense, since the scope of my invention is best defined by the appended claims.

Referring to the drawing:

Figure 1 is a side view, partly in section, of a dynamic loud speaker embodying my invention;

Fig. 2 is an enlarged detail, partly in section, showing the manner in which the coil supporting parts are arranged;

Fig. 3 is a view taken from the left of Fig. 2; and

Fig. 4 is a plan view of the flexible mounting member utilized for suspending the movable coil.

In this instance I show a cone type speaker, although other forms of speakers could be used in connection with my invention. In order to provide the strong constant magnetic field, there is an electromagnet arrangement, including a central core 11, and a coil

12 disposed around this core. An annular air gap is formed around core 11 so as to provide radial lines of force between the reduced portion 13 of core 11 and a surrounding circular pole piece 14 of magnetic material.

This pole piece is supported on the cylindrical housing 15, as by aid of the brackets 16. This housing also serves to complete the magnetic circuit, and to support the coil 12, thus forming a typical iron-clad magnet. A flange 17 disposed around core 11 and fitting

snugly into housing 15 serves effectively to maintain the annular air gap between core end 13 and pole piece 14 uniform.

The coil that carries the telephonic currents is tubular in form so as to permit it to encompass the extension 13 and thus to place its conductors transversely to the radial lines of force in the air gap. For this purpose,

a coil 18 (Fig. 2) of fine copper wire is wound in a groove on the outer surface of a hollow

cylindrical support 19. This support or spool is made from insulating material, such as bakelite, and is thin enough to pass easily between the pole piece 14 and the core extension 13.

It is now well known that a variation in current flow in coil 18 will cause a force to be exerted between the coil and the air gap, in an axial direction.

This is made use of to actuate an air actuator, such as a diaphragm or a stiff parch-

ment cone. The coil structure, including support 19, can be mechanically connected to the air actuator; and one of the features of my invention resides in the manner in which 5 the coil assembly is attached to the air actuator.

In this instance I show a cone 20 as of stiff paper or parchment, serving as the air actuator. Its edge can be left free if desired, 10 but I indicate it as fastened as by pasting, to a leather belt 21, which in turn is confined between the support 22 and the ring 23. The smaller end of the cone is glued or otherwise fastened to the inside of a metal conical cap 15 24. This cap can be provided with a series of apertures 25 to permit any excess fastening fluid to escape from between it and the cone 20.

The cap 24 has a tubular extension 26 (Fig. 20 2), between which and the conical portion there is an annular straight shoulder 27. The support 19 telescopes with the extension 26, as by being disposed thereover. A series of 25 prongs 28 struck up from extension 26 can be engaged in apertures 29 in support 19, to ensure against relative axial movement of these parts. However, the same result can be obtained by providing a tight fit between the parts 19 and 26.

20 In order to guide the coil 18 and its support 19 in an axial direction. I prefer to hang it flexibly, as by the aid of a flexible washer 30 shown in detail in Fig. 4. This washer has an inner ring portion 31 that fits over shoulder 27 and is clamped between it and the end of tubular support 19. The washer is also provided with an outer annular portion 32 where it can be clamped between the opposing faces of a clamping ring 33 (Fig. 1) and 40 a flange 34 (Figs. 1 and 3) formed on a supporting ring 35. This clamping can be effected by the aid of a series of screws 36 tapping into flange 34. The ring 35 can in turn be conveniently fastened on the outer surface 45 of pole piece 14, as by the aid of screws 37 engaging the ears 38 of ring 35. These ears are offset from the flange 34 so as to space the plane of washer 30 correctly with respect to the desired axial position of coil 18.

50 The two annular portions 31 and 32 of washer 30 are connected by a series of relatively long, flexible connections 39 (Figs. 3 and 4). Since the washer is made from thin flexible material, such as bakelite or varnished cambric, it is evident that although the rim 32 is confined against movement, the inner ring 31 can be flexed axially due to the give of the connections 39. This give is sufficient to permit the coil 18 to move axially in 55 accordance with the telephonic currents. It should also be noted that the connections 39 are nonradial, whereby their effective length is large and whereby great flexibility is assured. It is also evident that the movement 60 of coil 18 is guided due to this flexible sus-

penion so that it will remain properly centered in the annular air gap as it moves axially thereof.

By way of further explanation, it is pointed out that the connections or strips 39 40 are so disposed with respect to the coil and the fixed points that they are, when fixed to permit axial movement of the coil 18, subjected to twisting strain, which permits the coil to move axially without at the same time 75 permitting any radial displacement of the coil.

The two leads for coil 18 can be very conveniently brought out for external connections, and in such a way as to prevent any 80 rattling in the reproduction. Thus the leads 40, 41 can each be accommodated in a groove 85 such as 42, cut or otherwise formed on the exterior of support 19. These grooves connect at their left hand end with the annular depression in which the turns are supported, and at their right hand end, they serve to conduct the bare leads to the washer 30. The leads can be pasted or shellacked onto the washer, preferably along the arms 39, as 90 shown most clearly in Fig. 3. If necessary, a fabric covering 43 can be fastened over this portion of the leads. A pair of eyelets or bushings 44 is provided, one adjacent the outer end of each of a pair of connecting 95 members 39, for permitting the passage of the leads 40 and 41 to the outside of the washer 30, as clearly indicated in Fig. 1. These leads can then be fastened to any appropriate external terminals. 100

I claim:

1. In a signal transmitting device, means forming an annular magnetic air gap, a coil structure axially movable in said gap and arranged to carry the signaling currents, 105 means flexibly supporting said structure, said means having a portion that is confined against movement, another concentric portion that is fastened to the coil structure, the two concentric portions being substantially 110 coplanar, and flexible connections between said two portions; and leads for the coil fastened to said flexible connections.

2. In a movable coil structure for dynamic 115 reproducers, a tubular spool, a coil wound on said spool, a supporting member telescoping with one end of the tubular spool and supporting it, and a flexible guiding suspension for the coil fastened between the end of the spool and an annular shoulder on the support. 120

3. In a dynamic reproducer, a movable coil structure, and a flexible support for the structure, including a washer of flexible material, 125 said washer having an inner annular portion fastened to the coil structure, an outer annular portion spaced from the inner portion, said outer portion being adapted to be supported on a stationary support, and flexible arms connecting the inner and outer por- 130

- tions, said arms departing from radial direction in order to increase their effective length.
4. In a loud speaker of the electro-magnetic type, the combination of a coil adapted to move in a magnetic field, and a supporting means for said coil comprising flexible members extending outwardly therefrom in a non-radial direction to a support, said flexible members being disposed in a plane substantially at right angles to the direction of movement of the coil and having a length greater than the radial distance between said coil and said support.
5. In a loud speaker of the electromagnetic type, the combination of a coil adapted to move in a magnetic field, a support for said coil having flexible portions extending from said coil to fixed points, said flexible portions being of a length greater than the radial distance between said coil and said fixed points, and current carrying leads for the coil fastened to and extending along certain of the flexible portions between the coil and said fixed points.
6. In a loud speaker of the electro-magnetic type, the combination of a coil adapted to move in a magnetic field, and a support for said coil having spirally disposed flexible portions extending from said coil to a fixed point, said flexible portions extending substantially tangentially with respect to the axis of said coil whereby their flexibility is greatly increased.
7. A sound reproducer having a conical diaphragm, a magnetic driving means for said diaphragm, and means for supporting said diaphragm, said supporting means including a flexible support having a plurality of members, said members being non-radial with respect to the axis of said diaphragm, and inclined in a common direction with respect to their corresponding radii.
8. A sound reproducer having a diaphragm, a driving device for said diaphragm, and means for supporting said diaphragm, said supporting means including a flat flexible support having a plurality of members, said members being non-radial with respect to the axis of said diaphragm, and inclined in a common direction with respect to their corresponding radii.
9. A sound reproducer having a conical diaphragm, a driving device for said diaphragm, and means located adjacent the apex portion of said diaphragm for supporting said diaphragm, said supporting means including a flat flexible support having a plurality of members, said members being non-radial with respect to the axis of said diaphragm and inclined in a common direction with respect to their corresponding radii.
10. A sound reproducer having a conical diaphragm, a driving device for said diaphragm, and means for supporting said dia-
- phragm, said supporting means including a flexible support having a plurality of members, said members being non-radial with respect to the axis of said diaphragm, and inclined in a common direction with respect to their corresponding radii and spacedially separated for at least a part of their lengths.
11. A sound reproducer having a conical diaphragm, a driving device for said diaphragm, and means for supporting said diaphragm, said supporting means including a flat flexible support having a plurality of members, said members being non-radial with respect to the axis of said diaphragm and inclined in a common direction with respect to their corresponding radii and spacedially separated for at least a part of their lengths.
12. A sound reproducing device having a conical diaphragm, a driving device for said diaphragm, and means adjacent the small end of said diaphragm for supporting said diaphragm, said supporting means including means for permitting said diaphragm to rotate slightly about its axis as the diaphragm reciprocates in the direction of its axis.
13. In an apparatus for sound reproduction, a substantially rigid diaphragm having the form of a cone and adapted to vibrate as a whole, means for actuating said diaphragm comprising a pair of concentric pole pieces separated by an annular air gap, an actuating coil secured to the small end of said diaphragm and located in said air gap, and means for preventing lateral movement of said coil in said air gap including a support, said support having a plurality of flat flexible members all extending non-radially in the same cyclic sense with respect to the axis of the diaphragm.
14. In a loud speaker of the electro-magnetic type, the combination of a coil adapted to move in a magnetic field, and supporting means for said coil comprising flexible members extending outwardly with respect to the longitudinal axis of said coil, said flexible members extending in a non-radial direction between said longitudinal axis and a support, said flexible members being disposed substantially at right angles to the direction of movement of the coil and having a length greater than the radial distance between said longitudinal axis and said support.
15. In a signal transmitting device, means forming a magnetic air gap, a current-carrying coil adapted to move in said air gap, and a yielding support for said coil comprising flat strips of non-elastic flexible material extending outwardly with respect to the longitudinal axis of said coil, said flat strips extending to fixed points, said strips being positioned with respect to the coil and fixed points so that a twisting strain will be imposed upon said strips as the coil moves axially in said gap.
16. In a loud speaker of the electromag-

- netic type, an element adapted for reciprocal movement, and yielding supporting means for said element comprising a flat strip of flexible material extending from a point at which
- 5 it is secured for movement with said element to a fixed support, said strip being disposed in a plane transverse to the direction of movement of the element and being positioned with respect to the element and said
- 10 support so that a twisting strain will be imposed upon the strip as the element reciprocates.
17. In a loud speaker of the electromagnetic type, an element adapted for reciprocal movement, and yielding supporting means for said element comprising a spirally disposed flat strip of flexible material extending from a point at which it is secured for movement with said element to a support, said
- 15 flexible strip being disposed in a plane substantially at right angles to the direction of movement of the element and having a length greater than the straight line distance between the support and the point at which
- 20 it is secured for movement with the element.
18. In a loud speaker of the electromagnetic type, the combination of a substantially cylindrical shaped current-carrying coil adapted to reciprocate in a magnetic field and
- 25 along an axis common to the axis of the coil, and yielding supporting means for said coil holding the coil against radial displacement with respect to said axis as the coil reciprocates and comprising flat strips of flexible
- 30 material extending from points at which they are secured for movement with said coil to fixed supporting means positioned about said axis, said strips being positioned with respect to the coil and fixed supporting means so that
- 35 a twisting strain will be imposed upon said strips as the coil reciprocates.
19. In a loud speaker of the electro-magnetic type, the combination of a coil adapted to move in a magnetic field, and a support
- 40 for said coil having spirally disposed flexible portions extending from said coil to a fixed location, said flexible portions being of a length greater than the radial distance between said coil and said fixed location.
- 50 20. In a signal transmitting device, means forming a magnetic air gap, a current-carrying coil adapted to move in said air gap, and a yielding support for said coil comprising flat strips of flexible material extending outwardly from said coil to fixed points, said strips being positioned with respect to the coil and fixed points so that a twisting strain will be imposed upon said strips as the coil moves axially in said gap.
- 55 21. In an instrument of the class described, the combination of a conical diaphragm, means to actuate the diaphragm comprising a current carrying coil of relatively fine wire secured to the diaphragm adjacent the apex
- 60 of the latter and disposed in a magnetic air gap for movement in the direction of movement of the axis of the diaphragm, a flexible aligning device permitting movement of the coil in the desired direction and restraining any movement in a direction transverse thereto, and current carrying leads for the coil ends connected to the latter at points secured to the aligning device.
22. A sound reproducer comprising a substantially conical diaphragm, means forming a magnetic air gap, a current carrying member secured to the diaphragm adjacent its apex and disposed in the gap for movement in the direction of the axis of the diaphragm, means for maintaining the current carrying member in spaced position within the gap, comprising a plurality of flexible arms extending out from said current carrying member to fixed supporting means, and leads for the current carrying member mounted upon said flexible arms.
23. In an electrodynamic loud speaker, a magnetic field unit having an air gap, a sound reproducing diaphragm, an actuating coil secured to said diaphragm and adapted to move in said air gap, an outwardly extending flexible centering support for said coil, and flexible leads from an external circuit connected to the ends of said actuating coil at points along said flexible centering support.
24. In a loud speaker of the electromagnetic type, an element adapted for reciprocal movement and yielding supporting means for said element comprising flexible members extending non-radially with respect to the axis of said element from a point at which they are secured for movement with said element to a fixed support, said flexible members being disposed in a plane substantially at right angles to the direction of movement of the element and having a length greater than the straight line distance between the support and the points at which they are secured for movement with the element.
25. A sound reproducer comprising a substantially conical diaphragm, means forming a magnetic air gap, an actuating coil secured to the diaphragm adjacent its apex and disposed in the gap for movement in the direction of the axis of the diaphragm, flexible means extending outwardly from said coil to fixed points for securing said coil in spaced position within the gap while permitting it to move freely in the desired direction, said coil including a number of turns of fine wire, the ends which are secured to a face of said flexible means and extend for an appreciable distance thereon.
- In testimony whereof I have hereunto set my hand.
- HERBERT E. METCALF.
